Attorney's

UNITED STATES PATENT OFFICE.

KARL POTSCHNER, OF DOVER, OHIO.

WRENCH.

Application filed February 1, 1923. Serial No. 616,327.

To all whom it may concern:

Be it known that I, KARL POTSCHNER, a citizen of the United States, residing at Dover, in the county of Tuscarawas and State of Ohio, have invented certain new and useful Improvements in Wrenches, of which the following is a specification.

This invention relates to wrenches and more particularly to a type of wrench including a frame having an integral handle and jaw, a movable jaw slidably mounted in the frame and a lever pivotally mounted in the frame and provided with means for releasably engaging the slidable jaw in various adjustments, and is a continuation of my copending application, Serial No. 606,840, filed December 14, 1922.

The objects of the invention are to provide a wrench of this type in which the lever is pivoted upon a fixed or solid pivot in the frame, instead of the usual movable or shiftable pivot, commonly used in wrenches of this general type; to provide means for releasing the engagement of the lever with the movable jaw, without shifting the point of pivotal connection between the handles; to provide means for easily and readily disengaging the movable jaw from the lever and reengaging the same in a different adjustment; to provide means for limiting the extreme positions of the movable jaw to relieve the strain upon the engaging parts and to permit the lever and handle to operate within a convenient radius; and to provide a transverse opening entirely through the frame, one wall of which acts as a stop to limit the opening movement of the lever, the opening also making visible the working parts of the wrench to facilitate the adjusting of the movable jaw; and to generally improve and simplify the construction of wrenches of this general character.

The above and other objects may be attained by constructing the wrench in the manner illustrated in the accompanying drawings, in which—

Figure 1 is a side elevation of a wrench embodying the invention, parts being broken away for the purpose of illustration;

Fig. 2, a view similar to Fig. 1, showing the lever in the disengaged position;

Fig. 3, an edge elevation of the wrench; and

Fig. 4, a detached perspective view of the movable jaw.

Similar numerals of reference indicate corresponding parts throughout the drawing.

The frame 1 of the wrench is provided with the rigid jaw 2 and handle 3 which are preferably formed integrally with the frame. A passage 4 is formed entirely through the frame from one side of the same to the other and a keyhole slot 5 is broached out of the upper side of said passage and through the upper end of the frame.

A movable jaw 6 is constructed to slide back and forth in the frame toward and from the fixed jaw, and is provided on its lower side with the shank 7 having the round cross sectional portion 8 for engagement with the passage 4 and the flat portion 9 for engagement with the keyhole slot 5.

The under side of the round section 7 of the shank is cut away between points near opposite extremities of the shank in a plane substantially parallel with the track of the shank, spaced notches 10 being provided at intervals in said cut-away plane.

A slot 11 is cut through one side of the frame at approximately right angles to and terminating in the round passage 4 which forms a part of the track for the movable jaw. This slot terminates at its inner edge in the vertical wall 12, located adjacent to the opposite side of the frame, and is open through the diagonal rear edge 1^a of the frame.

A lever 13 is provided with the flattened upper end portion 14, which is received within the slot portion of the frame and pivotally connected thereto by means of the pivot pin 15. A stop lug 16 is formed upon the inner edge of the lever for engagement with the inner wall 12 of the slot to limit the closing movement of the lever and prevent pinching of the hand of the operator between the lever and handle.

The upper end of the lever is provided with the projection 17 arranged to selectively engage each of the notches 10 in the shank portion of the movable jaw 6. A stop lug 18 is formed near and at the inner side of the projection 17 to limit the opening movement of the lever.

A recess is formed back of and connecting with the slot or spline in the frame by drill-

ing or otherwise cutting a transverse hole 19 through the slotted portion of the frame, the center of this hole being preferably in a continuation of the plane of the inner wall 12 of the slot.

This recess permits the upper end of the lever to move into the position shown in Fig. 2, allowing the projection 17 thereon to just clear the cut-away, notched plane of 10 the shank of the movable jaw, when the stop lug 18 upon the lever engages the edge of the recess 19 as shown in said figure.

This opening 19 not only provides for a greater movement of the lever, but also 15 makes visible the internal mechanism of the tool at all times, greatly facilitating the adjusting of the movable jaw and lever to different positions; and simplifies the 20 method of manufacture by providing an unusually cheap manner of increasing the depth of the spline.

In the position shown in Fig. 2 with the stop lug 18 upon the lever in engagement with the rear wall of the recess 19, the movable 25 jaw is disengaged from the lever and may travel freely in either direction, within the limitations of the cut-away, notched plane, the extreme portions of the shank of the movable jaw limiting the movement in 30 either direction by engagement with the projection 17 upon the lever.

As the lever is moved toward the handle, the projection 17 thereon will enter the notch immediately before it and positively 35 engage the movable jaw for operation in this position. It should be noted that once the movable jaw is engaged by the lever, it is a physical impossibility for the same to become disengaged until the lever is again 40 moved to its extreme open position, shown in Fig. 2.

From the above, it will be obvious that this construction has eliminated the dependence upon springs, dogs or other additional 45 parts for holding the members in adjusted position, making it a physical impossibility for the movable jaw to disengage itself from the lever, excepting at the will of the operator.

It has furthermore provided a simple and effective means for keeping the movable jaw within its radius of usefulness, the extreme limit of the movable jaw in one direction bringing the same into engagement with the 55 stationary jaw as in the ordinary pliers, and the other extreme limitation of the movable jaw marks the maximum spread of the jaws as a wrench.

The primary object in producing this tool, 60 namely, to reduce all of the useful features of this class of wrenches to the utmost simplicity of construction, has been accomplished. It will be noted that the entire tool consists of three major parts and a 65 pivot pin and all the functions of the tool,

including the assembling or faculty of holding the same together, are found in these pieces.

The wrench is thus reduced to the absolute minimum of simplicity and number of 70 parts, and each piece in addition to performing its function in the operation of the tool, also provides means for keeping itself in position. Besides having a major function, each piece in addition is designed in 75 such a manner that it takes the minimum of labor and material to produce the same.

The walls between the notches in the movable jaw are lighter, or have less material in 80 them, than the projections 17, upon the lever, which engages said notches. This difference of strength is for a two fold reason. The projection on the lever will have to compensate for the sum total of all wear upon the 85 walls between all of the notches.

From a standpoint of strength, the projection is a continuation of the extreme end of the lever, making it obviously necessary that the same be heavier in order to equal 90 the strength of the walls between the notches, which are formed by cutting away transverse portions of the continuous shank.

The metal of the lever adjacent to the projection 17 is outlined by a radius, as 95 shown at 20, having the pivot 15 as a center, said radius engaging the extreme inner end of the shank and supporting the same when the jaw is in the extreme open position, as shown in Fig. 2.

In the normal spread and close of the operator's hand, the movable jaw will move to and from the stationary jaw far enough to permit the wrench to ratchet back and forth across the corner of a nut and reengage the same for another pull.

It will thus be seen that a simple and highly efficient tool may be manufactured at a price which the public can afford to pay for a wrench, this being made possible by the simplicity of construction, and the manner of constructing the three major parts of the wrench.

It may be desirable to provide a bushing around the pivot pin 15 as shown in Fig. 1 of the drawing, in order to cause the lever 115 to oscillate easily upon the pivot, and also to compensate for wear upon the pivot or the journal portion of the lever.

I claim:—

1. A wrench of the character described, 120 comprising a one-piece frame having a jaw integrally formed at one end and a handle integrally formed at the other end thereof, said frame having an opening therethrough in which are mounted a movable jaw and a 125 lever cooperating with each other in the same plane, a transverse hole in the frame, at substantially right angles to the opening and communicating therewith, said transverse hole furnishing means to limit the 130

opening movement of the lever whereby the lever may disengage and reengage the movable jaw in several positions without becoming entirely disengaged therefrom.

5. 2. In a wrench of the character described in claim 1, the transverse hole furnishing means for making the disengaging and reengaging of the lever and movable jaw visible.

3. In a wrench of the character described in claim 1, a stop on the under side of the lever for limiting the closing movement of the lever relative to the handle, for preventing pinching of the fingers.

In testimony that I claim the above, I 15 have hereunto subscribed my name.

KARL POTSCHNER.
